DESIGN FOR A COMBINED HOLDING AND DISPLAY RACK, FOR BROOMS OR THE LIKE

Clarence S. Anderson, Des Moines, Iowa, assignor to New Monarch Machine & Stamping Co.,
Des Moines, Iowa

Application May 17, 1940, Serial No. 92,424

Term of patent 3½ years

To all whom it may concern:

Be it known that I, Clarence S. Anderson, a citizen of the United States, and resident of Des Moines, Polk County, Iowa, have invented a new, original, and ornamental Design for a Combined Holding and Display Rack, for Brooms or the like, of which the following is a specification, reference being had to the accompanying drawing, forming a part thereof.

Fig. 1 is a front perspective view of a combined holding and display rack, for brooms or the like, showing my design;

Fig. 2 is a front elevational view;

Fig. 3 is an end elevational view; and

Fig. 4 is a top plan view thereof.

I claim:

The ornamental design for a combined holding and display rack, for brooms or the like, substantially as shown.

CLARENCE S. ANDERSON.
